GEAR PUMP UNIT

Arthur S. Johnson, Providence, R.I., assignor to Brown & Sharpe Mfg. Co., Providence, R.I., a corporation of Rhode Island

Application December 7, 1956, Serial No. 626,865

5 Claims. (Cl. 103—126)

The present invention relates to a pressure fluid gear pump, and is concerned more particularly with an improved construction and method of assembly of an external gear pump unit.

It is an object of the invention to provide a novel and improved gear pump which is simple, requires for its construction a minimum number of finished surfaces, and is readily assembled into an efficient self-contained unit.

It is a further object of the invention to provide a novel and improved integrally formed housing having formed therein bores to receive the several operating parts of an external gear pump, said bores being well adapted to provide an efficiently formed and simply shaped pumping chamber and fluid passages for said pump.

It is another object of the invention to provide a novel method of assembling an external gear pump unit of which the operating parts are supported within a single housing provided with two gear receiving bores entering the casing from opposite ends with their axes spaced apart a distance equal to the spacing between the centers of the meshing gears so that the two bores cut into one another radially and project past one another by an amount equal to the length of the pumping chamber in which said gears are received.

With the above and other objects in view as may hereinafter appear the several features of the invention consist in the devices, combinations and arrangement of the parts and in the method hereinafter described and claimed which, together with the advantages to be obtained thereby, will be readily understood by one skilled in the art from the following description taken in connection with the accompanying drawings, in which—

Fig. 1 is a side view of an external gear pump embodying the several features of the present invention, the casing being sectioned to show the pump gears and their supporting arbors;

Fig. 2 is an end view of the pump shown in Fig. 1 looking from the right, the gear mechanism and the bores in which this mechanism is housed being shown in dotted lines;

Fig. 3 is a sectional view in elevation taken on line 3—3 of Fig. 1;

Fig. 4 is a sectional view in elevation taken on line 4—4 of Fig. 1, and;

Figs. 5, 6 and 7 are sectional views similar to Fig. 1 illustrating the method of assembly of the gear mechanism in the housing; in which—

Fig. 5 shows the upper gear, its supporting bushing and arbor, the bushing and gear engaged thereby being seated against the finished inner end of the bore;

Fig. 6 shows the additional assembly of the lower gear and its supporting bushing which has been pushed inwardly so that the lower gear is seated at the end of its bore to the right; and

Fig. 7 is a final assembly view in which the arbor for the upper gear has been pushed inwardly again forcing the upper gear to the left while leaving the supporting bush-

2

ing in the position determined by its engagement with the lower gear.

The external gear pump here disclosed as embodying in a preferred form the several features of the invention 5 comprises an integrally cast housing 10 having formed therein two parallel bores 12 and 14 which form the entire receiving chamber for the moving parts of the gear pump. The upper bore 12 projects into the casing from the right hand end as viewed for example in Figs. 1, 5, 6 and 7, terminating at its inner end in a finished surface 16. There is also provided a further axial extension of the bore 12 in the form of a hole 18 which provides a bearing support for the inner end of the upper driving gear arbor hereinafter described. The lower bore 14 projects into the casing from the left hand end as viewed in Figs. 1, 5, 6 and 7, terminating in a finished surface 20. A further axial extension 22 of the bore 14 provides a bearing support for the lower gear arbor hereinafter described. It may be noted that the end of the hole 22 is extended 20 through the right hand end of the casing, being normally closed by means of a screw threaded plug 24.

The diameters of the respective bores 12 and 14 are chosen to receive the respective upper and lower gears 26 and 28 of the pumping unit with an additional allowance for clearance which may, for example, amount to between .001 and .002 inch. The axes of the two bores are further chosen to coincide with the axes of the two gears 26 and 28 when properly meshed.

As will be readily evident from inspection of the drawings, the two bores 12 and 14 are projected past one another by a substantial amount. Further the bores are sufficiently large to overlap or cut into one another. The bores with their respective finished end surfaces 16 and 20 extend past one another by an amount which is exactly equal to the axial dimension of each of the two gears with a small additional amount provided for necessary clearance.

The housing 10 is also formed, as best shown in Figs. 2 and 3, with a flat base 30, with a transverse inlet port 32 and with a transverse outlet port 34 leading respectively to and from the gear chamber above described, which may be generally designated at 36.

The upper gear 26 is fixedly mounted on a gear arbor 38 which, when assembled in the gear unit, as best shown in Fig. 1, is mounted at its left hand end in a sleeve bearing 40 mounted in the hole 18, and is also supported by a sleeve bearing 42 mounted in a bushing 44 which serves as a plug for the open end of bore 12.

The bushing 44 is rigidly secured in its adjusted position by means of a transverse pin or dowel 46 which is driven into a hole in the housing 10 and in the bushing 44. A water-tight fit between the bushing and the rotating arbor is effected by means of a gland which comprises a packing 48 mounted in an annular recess in the outer end of bushing 44, and a flanged sleeve member 50 which is forced tightly against the packing 48 by means of screws 52 seated in the flanged portion of sleeve 50 and threaded into the end of bushing 44. A liquid-tight fit between bushing 44 and housing 10 is provided by means of an O-ring 54 mounted in an annular groove in the outer periphery of bushing 44.

The lower gear 28 of the pumping unit is rigidly secured to an arbor 56 which is mounted at its left hand end as best shown in Fig. 1 in a sleeve bearing 58 provided in a hole 60 formed in a bushing 62 which is utilized to plug the open end of the bore 14. Adjacent its other end the arbor 56 is supported in a sleeve bearing 64 mounted in the hole 22 in the housing. The bushing 62 is secured to its adjusted position by means of a transverse pin or dowel 66 which is driven into a hole passing through the housing 10 and through the upper portion of the bushing 62. A liquid-tight fit is provided be-

tween the bushing 62 and the housing 10 by means of an O-ring 68 mounted in an external annular groove in the bushing 62.

Further in accordance with the invention applicant provides a novel method of assembling the moving parts of his external gear pump in the improved and simplified housing above set forth. The method by means of which the pump unit is assembled comprises the following steps.

The bearing 40 is initially assembled in housing 10 and bearing 42 in bushing 44. The upper driving gear 26 and the arbor 38 to which it is rigidly secured are then assembled with the bushing 44, the O-ring 54 and the sleeve 50. These parts are then inserted into the upper bore 12 of the housing from the right hand end, pressure being brought specifically against the bushing 44 which acts against the adjacent face of gear 26. The gear 26 is thus driven into the bore until it is engaged firmly against the finished end surface 16 of the bore, as specifically shown in Fig. 5. Bearing 64 is assembled in housing 10, and bearing 58 in bushing 62. The lower driving gear 28 of the unit together with the arbor 56 to which it is rigidly secured are similarly assembled with the bushing 62, the assembled parts then being inserted into the lower bore 14 of the housing from the left hand end. Pressure is brought specifically against the bushing 62 which acts against the adjacent face of gear 28 so that the gear 28 is moved to the right until its rests firmly against the finished surface 20 forming the inner end of the lower bore 14. During the movement of the gear 28 to the right the gear will be brought into engagement with a lower portion of bushing 44 and will cause the bushing to be retracted so that the inner end face of the bushing 44 is flush with the finished surface 20 of the inner end of bore 14. Inasmuch as the bushing 44 is now located in its final position of adjustment, pin 46 is driven home thus locking the bushing 44 in position in the housing. During the inward movement of the bushing 62 and gear 28 above described, the bushing 62 will move slightly beyond the end face 16 of the bore 12 so that the bushing 62 will engage and move the gear 26 to the right, this being the position of the parts specifically shown in Fig. 6.

The next step in the assembly operation consists in the forcing of the arbor 38 and driving gear 26 of the upper gear unit to the left so that the inner face of the gear 26 is again brought into contact with the end surface 16 of the bore 12. During this operation the inner face of the gear 26 is also brought into engagement with the inner face of the bushing 62 which is again forced outwardly until the inner face of the bushing 62 is brought flush with the face 16 of the bore 12. This represents the finally adjusted position of the bushing 62 which is now locked in said position by the insertion of the dowel 66.

In the event that it is necessary to dis-assemble the unit the two pins or dowels 46 and 66 are driven out, thus releasing the respective bushings 44 and 62. The plug 24 is withdrawn and a suitable tool is inserted to drive the lower gear unit out of the lower bore 14. A suitable tool may then be inserted into the lower bore against the adjacent face of the gear 26 which is then driven out of the upper bore together with the associated parts of the upper gear assembly.

The invention having been described what is claimed is:

1. An external gear pump unit which comprises a driving gear and its supporting arbor, a driven gear and its supporting arbor, said driving and driven gears being of the same length, a one-piece housing having formed therein two parallel bores entering and extending only partially through the housing from opposite ends, of which the axes of said bores coincide with the axes of the respective gears when meshed, the diameters of the respective bores are the outside diameters of the respective gears with a small allowance added for clearance, said bores being projected past one another by an amount equal to the

length of the respective gears with a small allowance added for clearance, each of said bores having a finished inner end face, thus providing a gear chamber having the circumferential contours and length of said chamber accurately determined in accordance with the diameters and lengths of said gears, holes in said housing forming axial extensions of the respective bores to provide support for the respective arbors, bushings located in said housing having the outside diameters gauged to close said bores and inner end faces finished to provide end faces for the gears in said chamber and drilled to provide supports for the respective gear arbors, and means for pinning each bushing to the housing in an axially adjusted position in the respective bore in which said finished face of each bushing is flush with said finished inner end face of the adjacent parallel bore.

2. An external gear pump unit in accordance with claim 1 in which the driving gear with its supporting arbor and the driven gear with its supporting arbor are formed as integral one piece units.

3. An external gear pump unit in accordance with claim 1 in which that portion of the supporting arbor for the driving gear through which the drive is taken is mounted in the associated bushing and a lubricant pressure sealing device is connected between said driving arbor and said associated bushing for sealing fluid under pressure within the pump chamber.

4. The method of assembling an external gear pump unit having a driving gear, a driven gear, a driving arbor to which the driving gear is fixed, and a driven arbor on which said driven gear is supported, a one-piece housing with two parallel bores of sufficiently large diameter to receive said gears entering the housing from opposite ends along the rotational axes of said gears when meshed, and an arbor supporting bushing closing the open end of each of said bores, said bores having the end faces thereof projected past one another to form a gear chamber within the housing, the length of said chamber being accurately determined to receive said gears, which method comprises the steps of projecting the driving arbor, the driving gear and associated bushing into one of said bores, exerting pressure against the bushing to push the driving gear against the end face of the bore, thereafter projecting the driven arbor, the associated driven gear and bushing into the other one of said bores, exerting pressure against said latter bushing to force the driven gear against the end face of the said second bore and at the same time said driven gear engaging and retracting said driving gear bushing flush with said end face of the second bore, and thereafter advancing the driving arbor and gear independently of the associated bushing against the end face of the first mentioned bore, and at the same time said driving gear engaging and retracting said driven arbor bushing flush with the end of the driving gear supporting bore.

5. The method of assembling an external gear pump unit having a driving gear, a driven gear, a driving arbor to which the driving gear is fixed, and a driven arbor on which said driven gear is supported, a one-piece housing with two parallel bores of sufficiently large diameter to receive said gears entering the housing from opposite ends along the rotational axes of said gears when meshed, and an arbor supporting bushing closing the open end of each of said bores, said bores having the end faces thereof projected past one another to form a gear chamber within the housing, the length of said chamber being accurately determined to receive said gears, which method comprises the steps of projecting the driving arbor, the driving gear and associated bushing into one of said bores, exerting pressure against the bushing to push the driving gear against the end face of the bore, thereafter projecting the driven arbor, the driven gear and supporting bushing into the other of said bores, exerting pressure against the latter bushing to force the driven gear against the end face of said second bore, while the latter

bushing pushes against and retracts the driving gear and the driven gear engages and retracts the driving bushing flush with the end face of the latter bushing, securing the first mentioned bushing in position in the housing, thereafter advancing the driving arbor and driving gear against the end face of the bore while the driving gear engages and retracts the driven arbor bushing flush with

the end face of the driving arbor supporting bore, and securing the latter gear bushing in position in the housing.
